RELEASING END STOP SLIDE FASTENER

William Mikulas, West Brighton, Staten Island, N. Y., assignor to Conmar Products Corporation, Newark, N. J., a corporation of New Jersey

Application September 30, 1943, Serial No. 504,414

8 Claims. (Cl. 24—205)

This invention relates to slide fasteners and more particularly to separable slide fasteners embodying a releasing end stop.

In separable slide fasteners provided with a releasing end stop, one of the pair of stringers that make up the slide fastener, which stringers are made fully separable at one end such as the bottom end, is provided with a so-called releasing end stop at the other such as the top end, which functions as a normal stop for the slider and as a releasing stop when a greater than normal force is exerted on the slider to force the same past such stop.

In operation, the slider when drawn with normal force to complete the closing of the slide fastener stringers engages and is stopped by the releasing end stop. For the purpose of making it possible to quickly open the slide fastener (i. e., without having to draw the slider back to the separable ends of the fastener), a greater than normal force exerted on the slider in the fastener closing direction causes the slider to move past and thereby become released by the releasing end stop and its stringer, whereupon the stringers are free to be separated by a stripping action. To retain the slider on the slide fastener, the slide fastener elements on the other stringer are made to extend beyond the position of the releasing end stop and a permanent end stop is provided at the end of such slide fastener element extension. When the slider is released from the releasing end stop and its stringer, it is held or retained on the extension end of this other stringer.

The releasing end stop has to serve efficiently its dual function of acting as a stop during normal use and as a releasing means during abnormal use. The releasing action is intended to be brought into play in case of an emergency, as when the slider cannot be moved normally in slide fastener opening direction (for example, when movement thereof is obstructed or jammed) or as when confronted by a dire emergency, time forbids such normal opening use. The releasing end stop must, therefore, be constructed so that it is thoroughly reliable in its dual acting capacity. Strength and durability are related important features. Also in construction, form and appearance, it must be compatible with the structure of the slide fastener itself. The prime object of my present invention pertains to the provision of a releasing end stop and a slide fastener embodying the same, which satisfy these requirements to an optimum degree.

To the accomplishment of the foregoing and such other objects as may hereinafter appear, my present invention relates to slide fasteners embodying the improved releasing end stop as sought to be defined in the appended claims and as described in the accompanying specification

taken together with the drawing illustrating the same, in which:

Fig. 1 is a front elevational view of a slide fastener constructed to embody the principles of the present invention and illustrating the normal stop action of the releasing end stop thereof;

Fig. 2 is a similar view showing the upper end of a slide fastener and illustrating the releasing action of the releasing end stop;

Fig. 3 is a view taken in cross-section in the planes of the lines 3—3 of Fig. 2 and showing the construction on an enlarged scale; and

Fig. 4 is a perspective view of the releasing end stop itself separated from the stringer tape to which it is normally constructionally attached.

Referring now more in detail to the drawing, the slide fastener, of the fully separable type, comprises the usual pair of stringers S and S' consisting of the beaded tapes t and t', the tape t being provided with the slide fastener series f and the tape t' being provided with the mating slide fastener series f', each slide fastener series consisting of a plurality of spaced slide fastener elements clamped to the beaded edge of the tape.

20 The slide fastener is openable and closable in the usual way by the action of a slider such as the conventional slider 10 which, when moved downwardly by the slider pull 12, opens the stringers of the slide fastener by causing the unlocking of the slide fastener elements, and which, when moved upwardly by the slider pull 12, closes the

30 stringers of the slide fastener by causing the interlocking engagement of the fastener elements f and f'. The slide fastener is of the fully separable type and, therefore, includes the retaining member or socket 14 at one end such as the bottom end of the slide fastener permanently fixed to a pin 16 clamped about the lower end of the beaded edge of the tape t, and a movable pin 18 clamped about the lower end of the beaded

25 edge of the tape t', the said pin 18 being removably receivable by the socket 14. As is well known, when the slider 10 is at its lowermost position on the slide fastener and in engagement with the top of the socket 14, the pin 18 may be threaded out of or into the slider 10 when separation and assembly of the slide fastener stringers are respectively desired.

The releasing end stop of my present invention, 50 generally designated as 20, is located at the opposite or closed end of the slide fastener and is designed to act normally as an end stop for the slider as depicted in Fig. 1 of the drawing, and under other than normal conditions, as a means for releasing the slider and permitting a quick stripping separation of the stringers as is depicted in Fig. 2 of the drawing. For retaining the slider on the slide fastener when and after the slider is released from the stringer which carries the releasable end stop, the slide fas-

tener elements on the other stringer are made to extend in a short series f^2 beyond the position of the releasing end stop 20, and a permanent end stop 22 is provided at the end of such slide fastener element extension f^2 . When the slider is released from the end stop 20 and its stringer S', it is held or retained on the extension end f^2 of the other stringer S as clearly shown in Fig. 2 of the drawing.

The releasing end stop 20 comprises a pair of supporting elements 24 and 26 fastened to the opposite sides of the tape t' of the stringer S' at the closing end thereof and a releasing spring generally designated as 28 anchored at its opposite ends 30 and 32 to said oppositely disposed supporting elements 24 and 26 respectively, the said spring 28 being provided with an intermediate portion 34 which extends transversely through the supporting elements 24 and 26 and the tape t' in a position to engage the top inclined wall 36 of the slider at both sides of the tape, thus forming a normal end stop for the slider. This spring 28 functions as the normal stop for the slider and as the releasing means when a greater than normal force is exerted on the slider 10 to force the top inclined wall 36 thereof past the said intermediate and engaging portion 34 of the spring.

The supporting elements 24 and 26 are preferably made from a single piece of sheet material bent to form a U-shaped member as most clearly shown in Figs. 3 and 4 of the drawing, the same being formed to provide a socket edge 38 folded about and enclosing the beaded edge 40 of the tape t' and two wing elements which form the plate shaped supporting elements 24 and 26 referred to, which overlie and engage the opposite sides of the tape. This U-shaped member is secured or fastened to the tape t' by means of one or more rivets, two being shown in the exemplification of the invention depicted in the drawing, the said rivets 42 and 44 serving to fasten the supporting elements 24 and 26 together and to fasten this member to the opposite sides of the stringer tape t'. It will be noted that this U-shaped member is symmetrical with respect to the longitudinal plane of the tape.

The stop and releasing spring 28 comprises a spring element bent to the shape and configuration best depicted in Figs. 3 and 4 of the drawing, the ends or termini 30 and 32 of which, anchored as aforesaid to the supporting elements 24 and 26, are secured in position by the heads of the rivet 42 as best shown in Fig. 3 of the drawing, and the intermediate or medial portion 34 of which extends transversely through registering slots 46 and 48 formed in the plates 24 and 26 and through a registering opening 50 formed in the tape. The spring 28 also, therefore, forms a unit or element which is symmetrical with respect to the longitudinal plane of the tape t'. The region of the spring on each side of the tape located between the anchoring end and the intermediate or medial portion of the spring is looped about and retained within the extending head of the rivet 44 (on each side of the unit).

By means of this described construction, the following important functions and advantages are obtained. The stop and releasing spring 28 is symmetrically disposed with respect to the longitudinal plane of the tape and, therefore, the wear of the spring on the slider 10 and particularly the top inclined wall 36 of the slider is distributed on both sides or halves of the slider. The spring 28 comprising as it does a section on

each side of the tape, which sections are connected together by means of the transverse portion 34, is positioned on both sides of the slide fastener thus inhibiting the possibility or danger of being picked or forced away from the wings or plates 24 and 26 of the support by the action or movement of the slider. The intermediate or medial portion 34 of this spring provides a line contact and, therefore, an extended contact with the slider top causing less wear to any given point of the slider. The releasing force exerted by the slider on the spring and the reactive force are symmetrical with respect to the medial plane of the slide fastener and, therefore, the releasing action is a uniform one, free of any torsional strains or jerks. The arrangement of the spring as shown provides for a large effective spring length and, therefore, permits the use of a relatively strong spring (as is desired for the stopping action) and one having a high degree of resiliency (as is desired for the releasing action). Also the spring is bent outwardly in such a way that it bears efficiently against the upper ends of both halves of the slider. As a result, the releasing end stop of the present invention is thoroughly reliable in its dual acting capacity, serving efficiently as an end stop and as a releasing means.

For strengthening the anchorage of the U-shaped supporting member on the tape t', this member may be notched as at 52 to provide space to surround the last element 54 of the element series f', this corresponding to the interconnection between the permanent end stop 22 and the last fastener element 56 of the series f', where the fastener element 56 braces stop 22 thus helping to prevent the stop 22 from being displaced or twisted when the slider is pulled up with great force against the permanent end stop 22.

The construction and operation and the uses and advantages of the releasing end stop slide fastener of the present invention will in the main be fully apparent from the above detailed description thereof. The slide fastener is of the fully separable type and the stringers thereof may be separated in the usual way by drawing the slider 10 downwardly to its bottommost position and by then withdrawing or threading the pin 18 of the stringer S' through and from the slider 10. For closing the slide fastener, the slider 10 is moved to the position shown in Fig. 1 of the drawing, at which point the slider, and particularly the top walls 36 of the two slider halves, is engaged and stopped by the intermediate transverse portion of the spring 28. When a greater than normal force is exerted on the slider in the fastener closing direction, a camming action between the walls 36 of the slider and the intermediate portion 34 of the spring takes place, and the slider is forcibly moved past and thereby becomes released from the stop spring 34 and, consequently, from the stringer S'. The stringers S and S' are, therefore, free to be separated by a stripping action as best shown in Fig. 2 of the drawing. To assemble the parts together again, the slider 10, retained by the stringer S in the manner shown in Fig. 2 of the drawing, is returned to its bottommost position ready for the threading reception of the pin 18 of the stringer S'.

I claim:

1. In a slide fastener, in combination with a pair of stringer tapes having interlockable slide fastener elements and a slider movable therewith, of a slider releasing end stop comprising a pair of supporting elements fastened to oppo-

site sides of one of the stringer tapes at the slide fastener end thereof, said elements being provided with registering apertures, and a releasing spring anchored at its opposite ends to said oppositely disposed supporting elements and provided with an intermediate portion which extends transversely through said apertures and the tape in a position to engage the top of the slider at both sides of the tape to form the end stop therefor, said spring functioning as a normal stop for the slider and as a releasing stop movable in said apertures when a greater than normal force is exerted on the slider to force the same in a direction longitudinally of said slide fastener past the said intermediate and engaging portion of the spring.

2. In a slide fastener, in combination with a pair of stringer tapes having interlockable slide fastener elements and a slider movable therewith, of a slider releasing end stop comprising a pair of supporting elements fastened to each other and to opposite sides of one of the stringer tapes at the slide fastener end thereof, said elements being provided with registering apertures, and a releasing spring anchored at its opposite ends to said oppositely disposed supporting elements and provided with an intermediate portion which extends transversely through the apertures of said elements and the tape in a position to engage the top of the slider at both sides of the tape to form the end stop therefor, said spring functioning as a normal stop for the slider and as a releasing stop movable in said apertures when a greater than normal force is exerted on the slider to force the same in a direction longitudinally of said slide fastener past the said intermediate and engaging portion of the spring.

3. In a slide fastener, in combination with a pair of stringer tapes having interlockable slide fastener elements and a slider movable therewith, of a slider releasing end stop comprising a pair of supporting plates fastened to opposite sides of one of the stringer tapes at the slide fastener end thereof, the said plates being provided with registering slots, and a releasing spring anchored at its opposite ends to said oppositely disposed supporting elements and provided with an intermediate portion which extends transversely through said slots and through the tape in a position to engage the top of the slider at both sides of the tape to form the end stop therefor, said spring functioning as a normal stop for the slider and as a releasing stop movable across said slots when a greater than normal force is exerted on the slider to force the same in a direction longitudinally of said slide fastener past the said intermediate and engaging portion of the spring.

4. In a slide fastener, in combination with a pair of stringer tapes having interlockable slide fastener elements and a slider movable therewith, of a slider releasing end stop comprising a U-shaped member folded about the beaded edge, and forming a pair of supporting elements arranged on opposite sides, of one of the stringer tapes at the slide fastener end thereof, said member being fastened to the tape therewith, said elements being provided with registering apertures, and a releasing spring anchored at its opposite ends to said oppositely disposed supporting elements and provided with an intermediate portion which extends transversely through the said

apertures and tape in a position to engage the top of the slider at both sides of the tape to form the end stop therefor, said spring functioning as a normal stop for the slider and as a releasing stop movable in said apertures when a greater than normal force is exerted on the slider to force the same in a direction longitudinally of said slide fastener past the said intermediate and engaging portion of the spring.

5. In a slide fastener, in combination with a pair of stringer tapes having interlockable slide fastener elements and a slider movable therewith, of a slider releasing end stop comprising a U-shaped member folded about the beaded edge, and forming a pair of supporting plates arranged on opposite sides, of one of the stringer tapes at the slide fastener end thereof, said plates being fastened together and to the tape by a rivet, said plates being provided with registering slots, and a releasing spring anchored at its opposite ends to said rivet and provided with an intermediate portion which extends transversely through said slots and through the tape in a position to engage the top of the slider at both sides of the tape to form the end stop therefor, said spring functioning as a normal stop for the slider and as a releasing stop movable in said apertures when a greater than normal force is exerted on the slider to force the same in a direction longitudinally of said slide fastener past the said intermediate and engaging portion of the spring.

6. In a slide fastener, in combination with a pair of stringer tapes having interlockable slide fastener elements and a slider movable therewith, of a slider releasing end stop comprising a U-shaped member folded about the beaded edge, and forming a pair of supporting plates arranged on opposite sides, of one of the stringer tapes at the slide fastener end thereof, said plates being fastened together and to the tape by two spaced rivets, said plates being provided with registering slots, and a releasing spring anchored at its opposite ends to one of said rivets and provided with an intermediate portion which extends transversely through said slots and through the tape in a position to engage the top of the slider at both sides of the tape to form the end stop therefor, said spring being looped about the other of said rivets in regions between the anchoring ends and intermediate portion thereof, said spring functioning as a normal stop for the slider and as a releasing stop movable in said apertures when a greater than normal force is exerted on the slider to force the same in a direction longitudinally of said slide fastener past the said intermediate and engaging portion of the spring.

7. The slide fastener combination of claim 1 in which the releasing end stop is on one of the stringer tapes as defined, in which the slide fastener elements on the other of the stringers extend beyond the releasing end stop, and in which there is a permanent end stop at the end of such slide fastener element extension.

8. The slide fastener combination of claim 4 in which the releasing end stop is on one of the stringer tapes as defined, in which the slide fastener elements on the other of the stringers extend beyond the releasing end stop, and in which there is a permanent end stop at the end of such slide fastener element extension.
